DESIGN FOR A DISPLAY BOARD OR THE LIKE

Joseph J. Fabacher, New Orleans, La., assignor
to Jackson Brewing Company, New Orleans,
La., a corporation of Louisiana

Application February 2, 1939, Serial No. 82,731

Term of patent 3½ years

To all whom it may concern:

Be it known that I, Joseph J. Fabacher, a citizen of the United States, residing in New Orleans, parish of Orleans, and State of Louisiana, have invented a new, original, and ornamental Design for a Display Board or the like, of which the following is a specification, reference being had to the accompanying drawing, forming part thereof, in which:

I claim:

The ornamental design for a display board or the like, substantially as shown.

JOSEPH J. FABACHER.
